Attorneys.

UNITED STATES PATENT OFFICE.

ANDREW GILBERTS, OF CHICAGO, ILLINOIS.

CONTACT BREAKER.

Application filed August 24, 1921, Serial No. 494,815. Renewed March 5, 1925.

To all whom it may concern:

Be it known that I, ANDREW GILBERTS, a citizen of the United States, residing at Chicago, in the county of Cook and State of Illinois, have invented new and useful Improvements in Contact Breakers, of which the following is a specification.

This invention relates to new and useful improvements in make and break devices and particularly to make and break devices for electric bells, buzzers, and the like.

One object of the invention is to provide a device of this character wherein the usual platinum contact elements are eliminated, with the result that replacement thereof is rendered unnecessary.

Another object is to provide a device of this character wherein the contact elements have sliding or wiping action with each other, with the result that they will be kept clean, and a good connection provided at all times.

Other objects and advantages will be apparent from the following description when taken in connection with the accompanying drawing.

In the drawing:

Figure 1 is a side elevation of a portion of the make and break portion of a buzzer, or the like, showing the invention with the armature in elevated position, as drawn up by the magnet.

Figure 2 is a similar view, but showing the armature as having fallen away from the magnet.

Figure 3 is a vertical transverse section on the line 3—3 of Figure 1.

Referring particularly to the accompanying drawing, 10 represents the usual electromagnet, mounted on a suitable base 11, and having the projecting core 12. Mounted on the base 11, adjacent the end of the core 12, is a yoke 13, the arms 14 of which extend vertically upward at opposite sides of the core end. Disposed between these arms 14, and pivotally supported thereon, for swinging movement toward and away from the core end 12, is a metal block 15, which forms the major portion of the armature. Mounted on the rear face of the armature block 15 is an insulated member 16, the same having a vertical channel 17 formed therethrough. Also mounted on the base, rearwardly of the armature block, and in position to serve as a rear stop therefor, is a block 18, through which is threadedly engaged a vertical screw

19. Secured to the rear face of the block 15, and extending vertically thereabove, is a spring finger 20, the same being mounted for flexing adjustment toward and away from the block by means of the screw 21, which is disposed through the spring and block. The upper end of the spring finger 20 is bent to present its convex face toward the rear, as clearly seen in Figure 1, and slidably disposed through the channel 17 is a spring member 22, the intermediate portion of which is formed with a slight bow, 22', to bear against the walls of the channel, whereby the spring member will be frictionally held within the channel, but permitted to slide therethrough, in a manner, and for a purpose to which reference will be made later herein.

The upper end of the spring member 22 is bowed in a direction opposite to that of the corresponding end of the spring finger 20, and in position to move into sliding contact therewith. The lower end of the spring member 22 is formed with an angularly turned foot 23 which is adapted to engage with an inclined block 24 mounted on the base 11, directly therebeneath.

Mounted on a support, carried by the base 11, and at one side of the support of the screw 19, is a ball-headed screw 25, which is constantly and metallically in contact with the socketed end of a metal arm 26, secured to the rear of the insulated member 16, and extending laterally therefrom. A wire 27 is connected to the screw 25 and leads to one side of a source of current (not shown). A wire 28 connects the other side of the source with the electromagnet, while a wire 29 leads from the coils of the magnet to the pivot of the block 15.

When the circuit through the battery, or source of current is closed, it will flow through the magnet, the armature block, the contacting ends of the spring members 20 and 22, to the metal arm 26, with which the spring member 22 is in metallic contact, and back to the source. Upon this completion of the circuit, the magnet will be energized and the armature drawn up to the core, with the result that the foot 23 will engage with the lower end of the screw 19. This engagement of the foot with the screw, and the movement of the armature toward the magnet core, causes the spring member 22 to be slid down through the

channel 17, so as to withdraw its upper end from contact with the upper end of the spring finger 20. The circuit is then broken between the spring members, when 5 the armature will fall away from the magnet. As the armature falls back, the foot 23 contacts with the block 24, with the result that the spring member 22 is again pushed up through the channel until its 10 upper end contacts with the upper end of the spring finger 20. This action is repeated as long as the circuit is closed 15 through the battery and magnet. The arm 26 remains in constant contact with the ball-headed screw so that current can readily flow through the spring member 22.

What is claimed is:

1. In a make and break means for an electro-magnet, an armature mounted for movement toward and away from the magnet, a spring finger on the armature and in metallic contact therewith, an insulated member carried by the armature and having a channel therethrough, a sliding spring finger frictionally supported in the channel and movable into engagement with the first spring finger upon movement of the armature away from the magnet, and into contact therewith when the armature moves toward the magnet.

2. A make and break device for an electro-magnet including a pivoted armature, a channeled insulating member carried by the armature, a stationary spring finger on the armature, a frictionally held spring finger slidable through the channeled insulating member into and out of contact with the stationary finger, a foot on the slidable

finger, means for engagement by the foot of the sliding finger for moving said finger 40 into contact with the stationary finger, and means engageable with said foot for moving said movable finger away from said fixed finger.

3. In a make and break mechanism, an 45 electric magnet, a movable armature associated with the magnet, a fixed contact finger mounted on said armature, a second contact finger mounted on the armature, insulated means for slidably attaching said last mentioned contact finger to said armature, means for actuating said last mentioned contact finger to contact with said other contact finger when said armature is 50 away from said magnet, and means for limiting the movement of said second contact finger to break the contact between said fingers when said armature is drawn up by said magnet.

4. The combination with the movable 55 armature of a magnet; of a relatively movable contact member carried thereby, an insulated support for said member, means for establishing an electrical connection between said contact member and said armature 60 when the latter is away from said magnet and positive means for breaking said electrical connection upon movement of said armature towards said magnet, said last mentioned means including an abutment 65 adapted to intercept and limit the travel of said movable contact member with said armature.

In testimony whereof I affix my signature.

ANDREW GILBERTS.
